United States Patent Office

Des. 201,927
Patented Aug. 10, 1965

201,927

TRASH RECEPTACLE OR SIMILAR ARTICLE

Don Taylor Dean, Plainview, Tex., assignor to Donjim Enterprises, Inc., Plainview, Tex., a corporation of Texas

Filed May 11, 1964, Ser. No. 79,922

Term of patent 14 years

(Cl. D58—17)

FIG. 1

FIG. 2

FIG. 4

FIG. 3

FIG. 7

FIG. 5

FIG. 6

FIG. 1 is a front elevational view of a trash receptacle or similar article showing my new design;

FIG. 2 is a side elevational view, which is identical to the side opposite;

FIG. 3 is a rear elevational view;

FIG. 4 is a top plan view;

FIG. 5 is a sectional view taken on line 5-5 of FIG. 7;

FIG. 6 is a sectional view taken on line 6-6 of FIG. 7; and

FIG. 7 is a vertical sectional view thereof taken on line 7-7 of FIG. 4.

The dominant features of my design reside in the portion shown in full lines.

I claim:

The ornamental design for a trash receptacle or similar article, as shown and described.
